UNITED STATES PATENT OFFICE.

JOHN A. BROCKHUIS, OF CINCINNATI, OHIO.

LOW-WATER ALARM.

SPECIFICATION forming part of Letters Patent No. 713,558, dated November 11, 1902.

Application filed October 26, 1900. Serial No. 34,409. (No model.)

To all whom it may concern:

Be it known that I, JOHN A. BROCKHUIS, a citizen of the United States, residing at Cincinnati, in the county of Hamilton and State 5 of Ohio, have invented certain new and useful Improvements in Low-Water Alarms, of which the following is a specification.

My invention relates to low-water alarms for steam-boilers. Its object is to provide a 10 simple reliable alarm mechanism which is readily accessible to be tested and to be reset without interfering with the operation of the boiler and without drawing off any considerable quantity of water therefrom.

15 It also consists in certain details of form and combination, all of which will be more fully set forth in the description of the accompanying drawings, in which—

Figure 1 is a cross-sectional diagram of a 20 boiler with my improvements attached thereto. Fig. 2 is a central vertical section through the water-column and low-water alarm. Fig. 3 is a detail view of the separated parts of the alarm, partly in section.

25 A represents the steam-boiler, B the boiler-flues, and C D pipes leading, respectively, from the upper and lower portions of the boiler to a water-column E, to which the water-gage F is preferably attached.

30 G represents test-cocks attached one above the other to the water-column, and H the low-water alarm, also connected to the water-column at a point above the upper row of boiler-flues.

35 I J represent valves located, respectively, in the pipes C D, by means of which the connection between the boiler and the water-column can be closed.

K represents a drain-cock for draining the 40 water-column.

The low-water alarm, as shown, is composed of a steam-whistle L, of ordinary construction, which is screwed into the outlet end of the valve M, with a fusible plug or washer N interposed between the whistle and valve, so as to normally cut off all connection between the parts. The valve M is connected by the nipple O with the water-column at the point vertically at which it is desired to sound the 45 low-water alarm, which is preferably a short distance above the top of the upper row of flues.

While I have shown a steam-whistle as the simplest form of alarm mechanism, other steam-actuated alarm mechanism might be 55 employed in place thereof, if desired, and I do not wish to limit myself to the particular form of alarm mechanism.

The operation is as follows: Water is placed in the boiler to the required height and heat 60 applied to generate steam. The valves I J are opened, admitting steam and water into the column E, in which the water rises to the same height as in the boiler, and submerging the mouth of the nipple O and the valve M 65 opened. The height of the water is indicated on the gage F and in case of damage to the gage can be ascertained approximately by means of the test-cocks G. As long as the water in the column remains above the mouth 70 of the nipple O the plug N is not heated above its fusing-point, and therefore remains in a solid state, closing the passage to the alarm, and prevents the escape of the water thereto. As soon, however, as the height of the water 75 is lowered, so as to admit the entrance of steam into the nipple O, the steam, which is of a higher temperature than that of the water, fuses the plug N, and the steam escapes to the alarm and attracts the attention of the 80 engineer, who feeds more water into the boiler, closes the valve M, and unscrews the alarm and puts a new plug in place.

It is often desirable to test the alarm to ascertain that it is in working order, which can 85 be readily done by closing the valve J and opening the drain-cock K, when the water from the column will escape and permit the steam to enter the nipple O and sound the alarm, which can then be reset and the valve 90 J opened to let the water from the boiler into the column. In the devices heretofore in use it has been necessary in order to test the alarm to draw the water from the boiler until it reached a point at which the alarm would 95 sound.

One advantage of my device is that it can be attached while the boiler is in operation by simply connecting it to the opening for the lower gage-cock or tapping the water-column 100 a short distance above the flue-level. By attaching it to the water-column it is more accessible and convenient than otherwise. This construction also avoids obstructing the inte-

rior of the boiler and water-column and dispenses with any special connection for testing according to law. It is also absolutely reliable and can be tested by simply blowing the water 5 out of the water-column long enough to permit the steam to melt the fusible plug, which usually requires only about a minute.

My attachment constructed as above described is extremely simple and cheap to 10 manufacture and apply, durable in use, and certain in action.

Having described my invention, what I claim is—

1. In a low-water alarm, a water-column 15 having near its top a steam connection with the boiler and near its bottom a water connection with the boiler, a single horizontal passage for steam and water leading directly from the side of the water-column below the

normal water-line thereof to the alarm having 20 a fusible plug interposed in said passage to normally close the same and be opened by the admission of steam, substantially as set forth.

2. In a low-water alarm, a water-column 25 having near its top a steam connection with the boiler and near its bottom a water connection with the boiler, a single passage for steam and water leading directly from the water-column below the normal water-line 30 and on the outside of said water-column, and a valve in the bottom of said alarm, substantially as set forth.

JOHN A. BROCKHUIS.
